ALEXANDER FROMHOLD, OF RUTHERFORD, NEW JERSEY, ASSIGNOR TO S. H. POMEROY COMPANY, OF NEW YORK, N. Y., A CORPORATION OF NEW YORK.

METAL WINDOW CONSTRUCTION.

1,096,294.

Specification of Letters Patent. Patented May 12, 1914.

Application filed August 7, 1913. Serial No. 733,479.

To all whom it may concern:

Be it known that I, ALEXANDER FROMHOLD, a citizen of the United States, residing in Rutherford, Bergen county, State of New Jersey, have invented certain new and useful Improvements in Metal Window Construction, of which the following is a specification, reference being had to the accompanying drawing, which forms a part hereof.

This invention relates to the construction of window sashes of sheet metal. Such window sashes are commonly made up of galvanized sheet iron of about twenty-two or twenty-four gage and the machines used in the bending of this sheet metal, as generally constructed, are adapted for the handling of sheet metal of about the gage referred to only. The employment of sheet metal of such gages necessitates a closed construction, that is, a formation of the sash in which the edges of the sheet of metal which forms any member of the sash must be brought together and secured by lapping or other equivalent means. Obviously such closed construction necessitates the use of a maximum quantity of sheet metal in superficial extent and also renders necessary a great number of operations in the formation of the complete member of the sash.

The object of the present invention is to reduce the cost of manufacture of windows of the class referred to and it has been found that a very considerable reduction of cost can be effected by the employment, in proper form, of sheet metal which is sufficiently heavy to permit the desired stiffness of the sash to be attained without necessitating a closed construction. Thereby the actual weight of metal employed is even less than in the closed construction by reason of the reduced superficial extent and the number of operations required in production of the sash is also reduced.

The invention will be more fully explained hereinafter with reference to the accompanying drawing in which it is illustrated and in which—

Figure 1 is a view in elevation of a double-hung window including both frame and sash, which embodies the invention. Fig. 2 is a view in section on the plane indicated by the broken line 2—2 of Fig. 1, on an enlarged scale and partly broken out to save space. Fig. 3 is a detail view in section on

the plane indicated by the line 3—3 of Fig. 1, also on an enlarged scale.

The window frame may be substantially of ordinary construction, comprising a head *a*, a sill *b*, and vertical side members *c*. Each of these members of the frame may be formed substantially in any usual or suitable manner. As shown in the drawing the head *a* is formed of two sheets of metal, *a*¹ and *a*² united as at *a*³ and *a*⁴, by folded joints. The under or facing member *a*² is formed with an offset or shoulder as at *a*⁵ for coöperation with the top of the upper sash and with a folded groove *a*⁶ also for coöperation with the top member of the upper sash. The sill *b*, having any desired form, has a vertical offset *b*¹ for coöperation with the lower rail of the lower sash. Each vertical side member *c* of the frame may be composed of four sheets of metal. One sheet *c*¹ forms the main body of the jamb. The two members *c*² are shown as secured to the first member *c*¹ by folded joints *c*³. The pocket or facing plate *c*⁴ is adjustably secured to the members *c*² by screws *c*⁵ which are passed through the members *c*² and are tapped into the pocket or facing plate *c*⁴. Setting up or backing off on the screws *c*⁵ draws the pocket forward toward the sash or permits it to move back away from the sash. The pocket or facing plate *c*⁴ is provided with a vertical channel *c*⁶ for the reception of the vertical rib *d*¹ of the parting strip *d*, which may be formed of two members *d*² and *d*³, secured together by folded, lapped joints as at *d*⁴. The member *d*² of the parting strip has on its rear face the projecting rib *d*⁵ which enters and fits closely within the vertical channel *c*⁶ of the pocket or facing plate *c*⁴. For clearness in illustration the rib *d*¹ is shown as fitting somewhat loosely in the channel, but it will be understood that it fits rather snugly therein. The parting strip may be secured in position by screws, one of which is shown at *d*⁶. The front member *d*³ of the parting strip is formed at its edges to engage the folded edges of the member *d*² and is also formed so as to provide a vertical channel *d*⁷ adjacent to each side of the parting strip.

The top rail *e* of the upper sash is open or U-shaped in cross section, having the outer and inner members *e*¹ and *e*² which are unconnected at their upper edges, and the face plate *e*³ which is bent to form a

shoulder e^4 to receive the glass f , the latter being secured in place by an angle bar f^1 fastened by screws f^2 to the top rail. The outer member e^1 coöperates with the shoulder a^5 of the head of the frame, both as a guide and as a weather-guard, while the inner member e^2 , being extended beyond the side rail e^1 , enters the vertical channel a^6 , forming an effective weather-guard.

- 10 The bottom rail g of the lower sash is formed substantially in the same manner as the top rail of the upper sash, but the inner and outer members g^1 and g^2 straddle the projection b^1 of the foot or sill b .
 15 The outer member g^1 may have an out-turned flange g^3 as a weather-guard. This bottom bar is formed, like the top bar of the upper sash, with a shoulder g^4 against which the glass is held by an angle bar g^5 secured by screws g^6 to the bottom rail.

The meeting rail h of the upper sash and the meeting rail i of the lower sash are constructed substantially like the top and bottom rails of the two sashes respectively, except that it is necessary, by reason of their peculiar functions, to add to each a separate strip h^1 and i^1 respectively, secured to the body of the rail or bar by any suitable means. Each is provided with a shoulder h^2 i^2 and with an angle bar h^3 i^3 . Each side rail k of each sash is also U-shaped in cross section, having outer and inner members k^1 and k^2 disconnected at their outer edges, while the face plate k^3 is formed with a shoulder k^4 against which the glass is held by an angle bar k^5 secured by screws k^6 to the side rail. The adjacent member k^1 or k^2 of the upper or lower sash, as the case may be, bears against the in-turned flange g^3 of the member c^2 of the frame, while the other member k^1 or k^2 , as the case may be, enters the vertical channel d^6 formed in the parting rail d . Each upper or lower sash is thus guided in its vertical movements and is effectively weather-guarded. The parting rail d , held by screws d^5 which are threaded into the pocket or face plate c^4 , may be adjusted independently of the pocket.

50 It will be observed that by the improved construction described not only is each sash

effectively weather-guarded but that, with the employment of sheet metal of proper weight, such as sixteen gage, every member of the sash is sufficiently stiff while the cost 55 of construction is reduced considerably through the reduction in quantity of material employed and through the reduction in the number of operations necessary for the formation of each member.

I claim as my invention:—

1. In combination, a sheet metal window frame having inturned edges, a pocket or facing plate secured thereto, a detachable parting rail independent of the pocket or 65 facing plate but secured thereto and having a vertical channel, and a sash having a side rail U-shaped in cross section with its edges unconnected and one member coöperating with the in-turned edge of the frame and the 70 other entering the vertical channel of the parting rail.

2. In combination, a sheet metal window frame having its side members formed with inturned edges, a pocket or facing plate 75 secured to the side member of the frame, a detachable parting rail independent of the pocket or facing plate but secured thereto and provided with two vertical channels and two sashes having each its separate side 80 rail formed of sheet metal U-shaped in cross section with its edges unconnected, one member of each side rail entering the corresponding channel in the parting rail and the other member coöperating with the in- 85 turned edge of the frame.

3. In combination, a sheet metal window frame having its side member formed with inturned edges, a pocket or facing plate secured to said side member and having a 90 centrally located vertical channel, a parting rail having a vertical rib to enter the channel of the pocket, and a sheet metal sash coöperating with the frame and the parting rail.

This specification signed and witnessed this 5 day of August A.D. 1913.

ALEXANDER FROMHOLD.
